UNITED STATES PATENT OFFICE.

JOHN W. MYERS, OF WATERVILLE, OHIO.

PURSE.

SPECIFICATION forming part of Letters Patent No. 577,057, dated February 16, 1897.

Application filed July 31, 1896. Serial No. 601,165. (No model.)

To all whom it may concern:

Be it known that I, JOHN W. MYERS, a citizen of the United States, residing at Water-ville, in the county of Lucas and State of Ohio, 5 have invented certain new and useful Im-
provements in Purses; and I do hereby de-
clare the following to be a full, clear, and ex-
act description of the invention, such as will
enable others skilled in the art to which it
10 appertains to make and use the same.

This invention relates to purses; and it con-sists in the novel construction and combina-tion of the parts hereinafter fully described
and claimed.

15 In the drawings, Figure 1 is a front view
of the purse. Fig. 2 is a cross-section taken
on the line *x x* in Fig. 1.

A is the body of the purse, consisting of a
20 band of flexible material, such as chamois
leather, folded double. The front *a* is not
quite as high as the back *a'*. The body A is
divided into compartments or pouches by
vertical rows of stitches *b*.

Three compartments are preferably formed,
25 but any desired number may be used. The
middle compartment B, which is a long one,
is provided with reinforcing-flaps *c* at its ends.
Each compartment is provided with a sepa-rate flap *d* at its top, stitched to or otherwise
30 firmly secured to the upper part of the back *a'*.

Each flap is provided with a means for se-curing it, such as a strap and buckle *d'*, but
any approved fastening device may be used
which will prevent the contents of the com-partment from working out.

The long compartment is preferably pro-vided with one or more loops *e*, secured to its
flap, and *e'* is a fastening-strap secured to one
40 end of the compartment and passed horizon-tally through the said loops. The strap *e'*
engages with a fastening, such as a buckle *f*,
a button, or a catch, at the other end of the
compartment and prevents the middle part
of the compartment from bulging, as well as
45 forming a means for securing the flap.

This purse is intended to be worn like a
belt, and preferably under the outer gar-ments.

G G' are straps or bands secured to the ends
of the purse for the purpose of securing it 50
about the waist of its owner. The flap of the
middle compartment is not made of the full
length of the compartment, and the flaps of
the end compartments overlap the ends of the
55 middle compartment. This permits the mid-dle flap to be raised and free access had to
the middle compartment without detaching
the belt from the body.

What I claim is—

1. In a purse, the combination, with a band 60
of flexible material provided with a long com-
partment, of a flap closing the top of the com-
partment, and reinforcing-flaps at the ends
of the said compartment, substantially as set
forth. 65

2. In a purse, the combination, with a band
of flexible material provided with a long com-
partment, of a flap closing the top of the com-
partment and provided with a depending loop,
and a fastening-strap attached to the ends of 70
the said compartment, passing through the
end of the said loop, and preventing the mid-dle
portion of the compartment from bulging,
substantially as set forth.

3. In a purse, the combination, with a band 75
of flexible material provided with a long mid-dle
compartment and short end com-partments,
of a flap closing the center portion of
the middle compartment, and flaps closing
the end compartments and lapping over the 80
end portions of the said middle compartment,
substantially as set forth.

In testimony whereof I affix my signature
in presence of two witnesses.

JOHN W. MYERS.

Witnesses:

H. C. MEISTER,
GEORGE JEFFERS.
